(57) CLAIM

The ornamental design for a child desk and chair set as shown and described.

DESCRIPTION

FIG. 1 is an upper, right, front perspective view of my new design for a child desk and chair set.

FIG. 2 is an upper, left, rear perspective view thereof.

FIG. 3 is a front elevation view thereof.

FIG. 4 is a rear elevation view thereof.

FIG. 5 is a right side elevation view thereof.

FIG. 6 is a left side elevation view thereof.

FIG. 7 is a top plan view thereof; and,

FIG. 8 is a bottom plan view thereof.

The broken lines shown in the figures depict portions of the child desk and chair set that form no part of the claimed design. The stippling in the drawings depict a contrast in appearance.
